CLAIM

The ornamental design for a shopping cart with bag hook as shown and described.

DESCRIPTION

This application is related to and incorporates by reference U.S. patent application Ser. No. 29/857,743, now U.S. Pat. No. D1,080,123 issued Jun. 17, 2025, filed on an even date herewith. It is understood that any material in U.S. patent application Ser. No. 29/857,743, now U.S. Pat. No. D1,080,123 issued Jun. 17, 2025, that is not present in this application forms no part of the claimed design.

FIG. 1 is a bottom, front, right perspective view of the shopping cart with bag hook showing our new design;
FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a top, front, right perspective view of the shopping cart with bag hook of FIG. 1 shown with additional unclaimed environmental subject matter; and,

FIG. 9 is a top, front, right perspective view of the shopping cart with bag hook of FIG. 8 shown with additional unclaimed environmental subject matter to illustrate one example of use.

In the drawings, the broken lines depict unclaimed subject matter only and form no part of the claimed design. The bolded broken lines in the drawings indicate the bounds of the claimed design and otherwise form no part of the claimed design.
